(57) **CLAIM**

The ornamental design for a blood pressure monitor, as shown and described.

DESCRIPTION

FIG. 1 is a perspective view of a blood pressure monitor showing the claimed design;

FIG. 2 is a front elevational view thereof;

FIG. 3 is a rear elevational view of thereof;

FIG. 4 is a left side elevational view of thereof;

FIG. 5 is a right side elevational view of thereof;

FIG. 6 is a top plan view of thereof;

FIG. 7 is a bottom plan view of thereof; and,

FIG. 8 is perspective view showing the blood pressure monitor in a usage state.

The broken lines depicting a blood pressure cuff and an arm in FIG. 8 are directed to environment and are for illustrative purpose only, while other broken lines are directed to portions of the blood pressure monitor that form no part of the claimed design; the broken lines form no part of the claimed design.
